United States Patent Office.

DAVID H. FANNING, OF WORCESTER, MASSACHUSETTS.

Design No. 4,617, dated January 31, 1871.

DESIGN FOR A CORSET.

The Schedule referred to in these Letters Patent and making part of the same.

To all whom it may concern:

Be it known that I, DAVID H. FANNING, of the city and county of Worcester and State of Massachusetts, have invented and produced a new and original Design for Corsets; and I do hereby declare that the following is a description of the same, reference being had to the accompanying drawing forming a part of this specification.

The design of the corset is fully illustrated by the drawing, in which the upper and lower parts, A and B, and the zone central part C, are united by vertical pieces D, the space a being filled with a net or lace-work fabric, the meshes of which are of the form shown in the annexed drawing.

I claim as my invention—

The design for corsets, substantially as shown and described.

DAVID H. FANNING.
